(57) CLAIM

The ornamental design for a nasal dilator device, as shown and described.

DESCRIPTION

FIG. 1 is a front perspective view of a nasal dilator device showing my design;

FIG. 6 is a left side elevation view of the nasal dilator device;

FIG. 7 is a bottom plan view of the nasal dilator device; and, FIG. 8 is a top plan view of the nasal dilator device.

1 Claim, 8 Drawing Sheets
